CAN OPENER

Arthur Carp, Ferguson, Mo.

Application April 28, 1958, Serial No. 731,200

11 Claims. (Cl. 30—15.5)

This invention relates to can openers, and with regard to certain more specific features, to hand-squeeze can openers of the so-called plier type.

Among the several objects of the invention may be noted the provision of a plier-type can opener which does not require the simultaneous use of two hands in order to effect can opening; the provision of a plier-type can opener which makes more convenient a can-opening operation, whether or not two hands are employed; the provision of a plier-type can opener which near the end of a can-opening operation allows freedom of one hand for holding and preventing the cut lid from falling into the contents of the can, thus disposing of the need for any magnetic and like devices heretofore used for such purposes; the provision of a can opener of the class described which makes it possible to open peculiarly shaped cans (such as, for example, sardine cans) which were heretofore difficult to open with such a plier-type can opener; and the provision of such a can opener which provides optimum conditions of operation and storage. Other objects and features will be in part apparent and in part pointed out hereinafter.

The invention accordingly comprises the elements and combinations of elements, features of construction, and arrangements of parts which will be exemplified in the structures hereinafter described, and the scope of which will be indicated in the following claims.

In the accompanying drawings, in which one of various possible embodiments of the invention is illustrated,

Fig. 1 is a plan view of my new can opener, showing it in cutting position on a sardine can;

Fig. 2 is a front elevation of Fig. 1;

Fig. 3 is a view similar to Fig. 2, except that the can opener is shown in open position and the can is not shown;

Fig. 4 is a cross section taken on line 4—4 of Fig. 2, showing in solid lines a closed untensioned position of a certain latch spring and in dotted lines a tensioned position of said spring;

Fig. 5 is a view similar to Fig. 4, showing in dotted lines a caught position of the latch spring and in solid lines the latch spring pushed into limited release position; and

Fig. 6 is a cross section taken on line 6—6 of Fig. 3.

Corresponding reference characters indicate corresponding parts throughout the several views of the drawings.

So-called plier-type can openers are favored by manufacturers over many other types of hand-operated can openers because the purchasing public prefers portability and instinctively knows how to use a pair of pliers. Therefore, no directions are ordinarily required to be furnished to the user for can-opening operations. This advantage to the manufacturer, however, is offset by certain disadvantages in the hands of the user. These include the fact that after the plier-like handles are squeezed together for an initial puncturing operation, they must be held together while the other hand operates the handle for rotating the usual traction wheel, in order to hold the traction wheel against the can bead for squeezing engage-

2

ment with the cutter wheel. Thus the hand which holds the plier type handles needs to furnish the resilience required for the squeezed cutter and traction wheels to ride over inequalities in the can bead and any vertical seams thereof. It is awkward to apply the correct amount of tension with one hand while the other is driving the traction wheel. In the second place, not all cans are round, some being more or less rectangular, like the sardine can illustrated. However, all shapes of cans rotate while the cutting operation is going on, unless the handles are released and the can held, allowing the opener to travel around the top. Rectangular and similar nonround cans, if left to rotate, will arrive at a position such as shown in Fig. 1, where a substantial part of the can extends along the side of the handles to a substantial extent. This prevents the handles from being properly gripped to produce the formerly required squeezing pressure above referred to. In the third place, when both hands are employed as stated and the end of the cut is reached, the cutout portion of the can may drop into its contents.

By means of the present invention, after the opener is initially squeezed into cutting position, the handles are no longer required to be squeezed, thus relieving one hand from the necessity of having a good grip, if any, on the plier handles. Thus a hand may be freed and used for removing the cutout portion of the can as it is released, and preventing it from dropping into the can contents. Or during the cutting operation this hand may hold the can while operating the traction wheel, allowing the can opener to move around the can margin, which is an operation that some persons prefer to letting the can rotate. Moreover, the present invention applies a constant resilient handle-holding pressure adapted for optimum cutting operations. Finally, as will appear, since no squeezing pressure is required on the handles to hold the opener in cutting engagement, the opener may be successfully used by children and infirm persons.

Referring now more particularly to the drawings, numeral 1 refers to a can, shown in broken lines, which is of an odd shape such as a sardine can, for the purpose of illustrating the invention. It is to be understood, however, that the invention is also advantageously operable on cans of other shapes, including round cans of all diameters. The latter usually have a vertical seam which is required to be traversed during the cutting operation.

The opener itself is constituted by pivoted lever members 3 and 5, joined by a pivot pin 7. The lever members 3 and 5 have plier-type handles 9 and 11, provided with exterior stiffening flanges 13 and 15, respectively. The flanges also serve as smoothly rounded palm and finger supports. The usual sloping pimple 17 on lever 3 carries a freely rotary sharpened cutter wheel 19. The lever 5 has a bearing 21 for a rotatable pin 23, to which is attached a toothed traction wheel 25. When the levers are pivoted on pin 7, the cutter 19 and traction wheel 25 may be brought from the separated position shown in Fig. 3 to the tangentially adjacent positions shown in Figs. 1 and 2. The traction wheel 25 is then positioned under a can bead such as 27 while the sharpened margin of the cutter presses the can top within the bead 27. A slot 29 in the lever 3 allows relative movement of a shoulder part 31 of the traction wheel. This shoulder extends through the lever 3 where there is attached a driving handle or key 33, for forceably rotating the traction wheel 25. The result of such rotation, provided the handles 9 and 11 are held together, is for the traction wheel 25 to progress along the bottom side of the bead 27 while the cutter 19 cuts along the inside of the bead and removes the can head. The head is indexed 35.

Numerical 37 indicates a transverse extension from the

lever 3 for engaging the top of the bead 27 to prevent tilting of the can or the cutter, as the case may be, as cutting progress is made around its margin. Numeral 39 indicates a lug for contacting the side of the can, to maintain can alignment with the cutter and traction wheel as such cutting progresses. Ribs 41 are for stiffening purposes.

At numeral 43 is shown a bowed ribbon type leaf spring, one end of which is folded over and anchored, as by welding, to the lever 3 near the base of its handle 9, as shown at 45. The other end of this spring is turned in to form a catch 47, adapted to engage the upper margin of the handle 11 at 49 when the handles 9 and 11 are together. When the handles are separated, the catch 47 is resiliently sprung into sliding engagement with the flat inside of handle 11 (see Figs. 3 and 6). This other end of the spring is also again turned to form a releasing finger pad 51.

As shown in the drawings, the flange 15 is provided with an extending portion 53, thereby effecting a notch 55 through which the pad 51 is movable. Extension 53 provides outward limiting movement for the unanchored end of the spring 43. However, the notch 55 is deep enough that after the catch 47 is pushed back from the margin 49, the catch 47 and pad 51 may move down to permit handle 11 to be separated from handle 9 (Figs. 3 and 6). Numeral 58 indicates an offset for bringing the sides of the handles 9 and 11 into a more or less common plane, particularly at the stop portions 57.

Operation is as follows, starting with the parts as shown in Figs. 3 and 6, wherein the handles 9 and 11 are separated:

An appropriate portion of a can bead is brought into position between the now-separated cutter 19 and traction wheel 25. Then with either hand the handles 9 and 11 are squeezed together, thereby bringing the traction wheel against the bottom side of the bead 27 and forcing the bead behind the cutter 19, the cutter entering the can top 35. Initially the closing action is limited by engagement between two adjacent stop portions 57 on the levers between the handles. This allows the catch 47 freely to spring in behind the margin 49. The angle at 47 is sufficiently oblique that a positive latching engagement is effected. The action is clear from Fig. 5, wherein it is shown that as the handles 9 and 11 come together the bowed spring moves from the solid- to the dotted-line locked position, its initial position when the handles 9 and 11 are open having been as shown in solid lines in Fig. 6.

It should be noted that while the sprung position of the bowed spring 43 changes in Fig. 5, its main curvature does not do so essentially. On the other hand, when, as is the desired purpose of the invention, the hand which initially squeezed the handles 9 and 11 together is removed, then the separating reaction of the bead 27 on the cutter 19 and traction wheel 25 tends to separate the handles, as shown in Figs. 2 and 4. However, the bowed spring 43 acts as a resilient latch, its bow tending to straighten as indicated by the dotted lines shown at 59 in Fig. 4.

Now, if desired, the hand may be released from squeezing handles 9 and 11, or these now-locked handles may be lightly held (without squeezing, if desired) and the key 33 turned, thus causing the cutter to progress around the bead 27 and remove the top or lid 35. Just before the cutting action is completed, the can top 35 will tilt and the hand that was on handles 9 and 11 may be employed to remove it as the cutting action is completed by final movement of the key 33. Moreover, if desired the hand that is not needed to hold the handles 9 and 11 together may be used to hold the can 1, thus allowing the cutter to progress around it as the key 33 is turned with the other hand. It will also be seen that when the can rotates into the position shown in Fig. 1, no hand is needed in any good gripping position on

handles 9 and 11, which it could not effectively assume in view of the interference from the can at this time.

If any variation in the thickness of a bead 27 is encountered, or any vertical seam in the can, the resulting required separating action of the cutter 19 and traction wheel 25 is accommodated by appropriate flattening of the bowed spring 43. Thus the spring acts not only as a catch but as a resilient tensioning device operating across the handles 9 and 11, so as resiliently to tension the cutter 19 and the traction wheel 25 on the bead 27. In this respect the invention is to be distinguished from the mere provision of a rigidly functioning latch between the handles 9 and 11, which would not allow the necessary resiliency for cutting various sizes of beads 27 on traversing vertical seams. A vertical seam is illustrated for example at 61 (Fig. 1), although such are usual mostly on round cans.

It will be appreciated that the catch 47 and the margin 49 together form an automatically operative closing latch when the handles 9 and 11 are together, as shown in Fig. 2, and that this latch will not reopen in response to separating forces. However, it will be understood that the flattening action of the bowed spring 43 allows of some resilient separating movements of the handles. This provides for resilient reactions to, and relative movements of, the cutter 19 and the traction wheel 25 as they traverse seams, various sizes of beads 27 or other can variations.

After a can-opening operation is completed, the catch 47 may be pushed aside, thus releasing the handles 9 and 11 for opening. Since 43 is a spring and should not be excessively deflected, engagement of the pad 51 with the extension 53 upon opening prevents the spring 43 from being bent beyond its elastic limit. This is a fairly important feature since the spring is intended to stretch by flattening out its bow while cutting proceeds, as indicated in Fig. 4. Thus it cannot be made indefinitely strong against sideward deflection; otherwise the flattening action under applied tension will not be effective enough.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. In a plier-type can opener having pivoted levers respectively carrying a cutter wheel and a cooperatively movable hand-driven traction wheel on one side of the pivot and squeeze handles on the other side of the pivot; the improvement consisting of resilient means forming a substantially resilient connection between the handles and having a catch automatically operative when the handles are brought together to place said cutter and traction wheels in cutting relationship under resilient reaction therebetween, the resiliency of said means when the catch is effective and the hand squeeze removed from said handles being adapted to provide sufficient relative movements under said reactions between said cutter and traction wheels that they will readily traverse various beads and seams on cans to which they are applied as the traction wheel is hand driven.

2. In a plier-type can opener having pivoted levers respectively carrying a cutter wheel and a cooperatively movable hand-driven traction wheel on one side of the pivot and squeeze handles on the other side of the pivot; the improvement consisting of a resilient member mounted on one of the handles and having a catch automatically engageable with a holding part connected with the other handle to form a latch when the handles are squeezed together to move said cutter and traction wheels

together into cutting relationship, the resiliency of said member being adapted to provide relative movements under reactions encountered by said cutter and traction wheels as they traverse various beads and seams on cans to which they are applied for opening purposes.

3. A plier-type can opener according to claim 2, wherein the handle part with which said catch engages to form a latch is provided with means forming a limiting stop adapted to limit deflection of said member upon release of the latch.

4. A plier-type can opener according to claim 2, wherein the handle part with which said catch engages to form a latch is provided with means forming a limiting stop adapted to limit deflection of said member upon release of the latch and including stop means between the handles limiting their application to one another to positions permitting said catch to hold the handles together.

5. A plier-type can opener according to claim 2, wherein said resilient member is constituted by a bowed leaf spring attached at one end to one lever and having a catch at its other end, the part on the other lever engageable with the catch forming therewith the latch which will not reopen under said resilient action.

6. A plier-type can opener according to claim 5, wherein said catch is provided with a finger-operated release part, and means engageable by said release part forming a stop to limit deflection of said spring upon release of the latch.

7. In a plier-type can opener having pivoted levers respectively carrying a cutter wheel and cooperatively movable hand-driven traction wheel on one side of the pivot and squeeze handles on the other side of the pivot; the improvement consisting of a bowed ribbon-type spring anchored rigidly at one end of its bow to one of the handles, the other end of the bow being resiliently free and formed as a catch, the other handle having a part engageable by said catch to form a positively-holding latch when the handles are squeezed together, the resilience of said spring effecting closure of the latch and its bow being adapted to flatten to provide resilient reaction to the action of said cutter and traction wheels when the latch is closed.

8. In a plier-type can opener having pivoted relatively flat levers respectively carrying a cutter wheel and cooperatively movable hand-driven traction wheel on one side of the pivot and squeeze handles on the other side of the pivot; the improvement consisting of a bowed ribbon-type spring anchored rigidly at one end of its bow to one of the handles, the other end of the bow

being resiliently free and formed as a catch resiliently sliding on a flat of the other handle when the handles are open, the other handle having a part engageable by said catch to form a positively-holding latch when the handles are squeezed together, the resilience of said spring effecting closure of the latch and its bow being adapted to flatten to provide resilient reaction to the action of said cutter and traction wheels when the latch is closed.

9. A plier-type can opener according to claim 8, wherein said other handle carries means limiting latch-opening movement of said spring.

10. In a plier-type can opener having cross-pivoted levers having upper and lower parts respectively, said parts respectively carrying a cutter wheel and cooperatively movable key-driven traction wheel, both on one side of the pivot and having connected lower and upper squeeze handles respectively on the other side of the pivot; the improvement consisting of resilient means forming a substantially resilient connection between the handles and having a catch automatically operative between handles when the handles are brought together, to place said cutter and traction wheels in forced cutting relationship under resilient reaction therebetween, and a transverse extension from said upper lever part adapted to engage the top of the can margin, thereby preventing rocking of the can opener when operated by means of one hand actuating the key, the other hand holding the can.

11. A can opener according to claim 10, wherein said resilient means comprises a bowed leaf spring anchored to the lower handle and having an offset portion adapted for releasable engagement with a holding part on the upper handle when the handles are brought together.
